1834

Samuel Lyon 2nd

Improvement in Manufacture of Matted Hair

DESCRIPTION:

The improvement consists in applying to use what has heretofore been considered worthless viz: "Goat-hair" or "Stringy hair of the kettle" which consists of cotton hair and fur so mixed together as not to be separable by any known process. The whole of it can be pressed dried and worked with wool, for the purpose of making matted hair, so as to constitute a compound part of hair bocies.

CLAIM:

The claim is for the converting the "Goat-hair" stringy or stringy of the kettle, to use.

Setters Patent.

The Schedule referred to in this Letter Patent, and making part of the same, containing a description in the words of the said Daniel Green ^{and} himself, of his improvement in the manufacture of Napped hats.

To all to whom these presents shall come,

Be it known that Daniel Green of Needham in the County of Norfolk & Commonwealth of Massachussets have discovered a new and useful improvement in the Manufacture of Napped hats, & that the following is a full and exact description and account of said improvement.

Said improvement consists in applying to a, ~~as~~ an ingredient in making napped hats, a material which hatters have heretofore thrown away as of no value, this material is known among workmen by the name of "Lodging sticker" or "Shimmings of the kettle" & is produced as follows. When in bowing naps, or layers for hats, a small portion of cotton or cotton-waste has been mixed with the fur, in a less significant part of the process, which is called napping, the whole of the cotton or waste will be disengaged or detached from the body of the hat, together with the principal part of the hair in the fur and a small portion of the fur itself, and the whole will float upon the surface of the water in the napping kettle. - This material consisting of cotton hair & fur, so mingled together as not to be separable by any known process, has heretofore been thrown away as worthless. The whole of it however, for the purpose of making napped hats, can be preserved, dried, and worked in with wool, so as to constitute a coarse

component part of hat bodies. -- What I claim as my improvement is, the converting to use, as above described this "Gum-strike" or "Skimmings of the kettle". --

A sample of this material together with a hat body into which a portion of it has been wrought, accompanies this application. --

In testimony that the above is a true specification of my said improvement as above described.

I have hereunto set my hand this fifth day of April in the year of our Lord eighteen hundred & thirty four in witness
